UNITED STATES PATENT OFFICE.

ROBERT HUDSON WAGER, OF JERSEY CITY, NEW JERSEY.

LATHER-FORMING DEVICE.

Application filed March 15, 1922. Serial No. 544,059.

To all whom it may concern:

Be it known that I, ROBERT H. WAGER, a citizen of the United States, residing at Jersey City, in the county of Hudson and State 5 of New Jersey, have invented certain new and useful Improvements in Lather-Forming Devices; and I do declare the following to be a full, clear, and exact description of the invention, such as will enable others skilled in the art to which it appertains to 10 make and use the same.

This invention relates to devices for making shaving lather without the use of the usual unsanitary shaving brush.

15 The principal object of the invention is to provide a simple and effective device which will make a lather of the proper consistency for use in shaving and which will be entirely sanitary.

20 Another object of the invention is to provide a device of this character in which the suds will be made into lather of the proper consistency for shaving by being passed through a plurality of screens and condensing 25 chambers.

Another object of the invention is to provide a device of this character in which an ordinary cake of shaving soap may be used and will be retained in the device in a 30 strictly sanitary condition.

Another object of the invention is to so construct this device that the lather may be formed in the container by causing air to be passed about the cake of soap in the container and through water in which the soap is placed thus creating soap-suds which will pass through a condensing means and pass out of the discharge nozzle in the form of lather.

40 Another object of the invention is to so construct this device that as the soap bubbles which are formed in the water and soap carrying compartment pass into and through the condensing means, the bubbles will be broken up and a thick lather produced which will emerge from the discharge 45 spout ready for use.

Another object of the invention is to so 50 construct this device that the air which passes through the water and about the soap may be admitted either from a container for air which will be placed under pressure or forced into the soap receptacle or compartment by means of a pump, such 55 as a bulb.

Another object of the invention is to pro-

vide means for directing the air towards the walls of the soap and water container, so that the air will be evenly distributed about the cake of soap which rests upon the distributor.

Another object of the invention is to provide the air inlet with an improved valve structure which will permit the air to enter but prevent the water from passing out 65 through the air inlet.

Another object of the invention is to so construct this device that it may be readily taken apart for cleaning.

A still further object is to provide a novel 70 process for condensing the soap bubbles to form a lather of the required thickness.

This invention is illustrated in the accompanying drawings, wherein:

Figure 1 is a view showing the improved 75 device in side elevation.

Figure 2 is a vertical partially sectional view through the device.

Figures 3, 4 and 5 are transverse sectional 80 views taken along the lines 3-3, 4-4 and 5-5 respectively of Fig. 2.

Figure 6 is a perspective view of the upper part of the device.

Figure 7 is a side elevation showing a modified form of the lather forming device, 85 partly in section.

Figure 8 is a side elevation showing another modified form of the device.

Figure 9 is a detail sectional view of a modified form of a condensing or lather 90 forming chamber for the device.

Figure 10 is a section on line 10-10 of Fig. 9.

This improved lather forming device is provided with a cup 1 in which the water and a cake of soap, soap powder or some liquid soap will be placed. It is provided with a filling neck 2 through which the water will pass into the cup. It should be noted that the filling neck is so located and shaped that only a certain amount of water may be held in this cup, this being preferably a sufficient amount for creating lather enough for one shave and particularly being such an amount that when the device is tilted, the water cannot leak out through the lather passage. This filling spout 2 will have the inlet opening closed by a suitable closure which in the present illustration is in the form of an inwardly opening valve 3 pivotally mounted at its upper end at 4 and provided with an abutment extension 5

so that its outward movement under the action of the spring 6 will be limited. Openings 7 and 8 are formed in this valve member so that when it is moved inwardly by being 5 brought into engagement with a spigot, the water from the spigot may pass through the openings 7 and 8 and into the cup 1 until the cup is filled to the level shown in Fig. 2. A depending neck 9 extends from the cup 1 10 and is inwardly thickened intermediate its length to provide a valve seat 10. The lower end portion of this neck is internally threaded as shown in Fig. 2 to receive the threaded upper end portion of the plug or 15 connection 12. This plug 12 is provided with an air passage 13, the upper end of which communicates with an air passage 14 leading to the seat 10 on which the ball valve 15 will be normally seated to prevent 20 water from flowing through the passage 13 to the source of air supply. In the form shown in Figs. 1 and 2, this plug has its lower end screwed into a threaded opening formed in the upper end of an air tank 16 25 which is provided with supporting feet 17 and a valve-controlled air inlet 18 so that this valve-controlled air inlet may be placed in engagement with a conduit pipe leading from a man air supply and compressed air 30 forced into the receptacle 16. This valve 18 is not specifically illustrated as any valve which will serve the purpose may be used and in the preferred form will have a construction similar to that used in connection 35 with automobile tires and the like. Bracing arms or bars 19 are provided between the tank and cup for strengthening and these bars may have their upper and lower ends connected with the cup and tank either by 40 brazing or the like or by means of removable fasteners such as screws. Since the tank 16 contains compressed air for passing through the passage 13, there has been provided a valve 20 intermediate the length of 45 the plug, the valve being provided with an actuating stem 21 terminating in a head 22 engaged by a spring 23 so that the valve will be normally held closed but may be moved to an open position. In the form shown in 50 Figs. 7 and 8, the cup does not need to extend below the neck 9 as far as in the form shown in Figs. 1 and 2, as these forms are not provided with the storage tank 16 and therefore the valve 20 is not necessary. In 55 the form shown in Fig. 7, the base 24 which carries the cup 1 will preferably be formed of relatively rigid material such for instance as hard rubber and this base will be provided with a flexible resilient rubber portion 60 25 so that when this flexible portion which may be termed a diaphragm is pressed inwardly, air in the base may be forced through the passage 14 of the neck. A valve-controlled air inlet 26 will be provided 65 in the base and will have a structure simi-

lar to those provided for the rubber bulb of an atomizer. In the form shown in Fig. 8, the base 27 may be formed of any material and will be provided with an air inlet neck having connected therewith the tube 28 70 which leads from the bulb 29. This bulb which is similar to those used for atomizers is provided with the usual valve-controlled air inlet 30 and when pressed will cause air to be forced through the tube 28 from which 75 it will pass through the passage 14 of the neck.

The cake of shaving soap 31 will be placed in the cup and will rest upon the platform 32 which fits into the cup and rests 80 upon the bottom thereof. This platform 32 is provided with a depending neck 33 and has its under face provided with curved ribs 34 which radiate from the depending neck so that air which passes up through 85 this neck and out through the side openings 35 will be directed toward the sides of the cup and caused to have a spiral motion through the water and about the soap. This will cause the water to be stirred to form 90 soap suds and as the air passes up through the water, soap bubbles will be formed in the cup 1 above the water. The neck 33 is screwed into the neck 9 above the valve seat 10 and is provided with a valve seat 36 for 95 engagement by the ball valve 15 which normally rests upon the valve seat 10. From an inspection of Fig. 2, it will be readily seen that normally this valve 15 will rest upon the valve seat 10 thus preventing any 100 possibility of water passing through the passage 13 into the air container. When however air is passing up through the plug 12 and neck 9, the valve ball will be unseated to permit the air to pass upwardly 105 through the water and about the soap to form soap bubbles in the cup. If the air should be under greater pressure than the normal amount or if the air is forced through the plug and neck too rapidly by means of the diaphragm 25 or bulb 29 in 110 the form shown in Figs. 7 and 8, this air which will be passing through the plug and neck too rapidly will cause the valve ball to be moved upwardly until it is seated upon 115 the upper valve seat 36. This will cut off the passage of air or reduce it to such an extent that the air will pass through the water at the desired rate of speed for the proper formation of the soap bubbles. These 120 soap bubbles as formed in the cup are too large to form a good thick lather such as is used for shaving and therefore the cover for this cup which carries the outlet spout has been provided with a construction whereby the soap bubbles are broken up and reduced to the proper size which will provide 125 a thick lather having the proper consistency for shaving.

The top 37 of this cup 1 is intended to be 130

screwed as at 38 upon the threaded upper end portion of the cup 1 and between this top and the cup is a bottom disk 39 having its central portion depressed to provide a well or seat 40 in which is formed an opening 41 through which the soap bubbles formed in the cup will pass. The disk 39 is clamped between an annular shoulder 42 in the cap 37 and the top of cup 1 as seen in Fig. 2. This cap 37 is provided with a centrally disposed sleeve or pocket 43 which is open at its lower end and provided with a side opening 44 so that the soap bubbles which pass into this sleeve or pocket 43 may pass out through the opening 44. A screen 45 which is formed of textile fabric, wire mesh or any other suitable material is placed in the seat 40 and held therein by means of a securing ring 46. It will thus be seen that when the soap bubbles pass through this screen they will be broken up and the bubbles after passing through the screen 45 will be smaller and the suds thus more condensed than they are in the cup 1.

A partition or rib 47 extends radially from the sleeve 43 to the side wall of the cap 37 between the outlet opening 44 of the sleeve and the passage 48 which extends upwardly from the interior of the cap through the discharge nozzle 49. Therefore, the suds which have partially formed into the proper consistency of shaving lather must pass around the sleeve 43. Before the suds reach the outlet passage 48 and pass upwardly through this passage and out through the small discharge ports 50 which are formed in the spout portion 51 of the nozzle 49, the bubbles in the suds are further condensed as they are not small enough to provide a thick lather having the proper consistency for shaving. Therefore there have been provided other screens 52 spaced about the sleeve 43 and extending between the sleeve and the depending wall of the cap. In the present illustration, two of these screens 52 have been shown but it will be obvious that as many may be provided as may be found desirable. After the lather has passed through these screens, it will be reduced to the proper consistency and will pass through the passage 48 and out through the ports 50. By passage through a plurality of relatively small openings or ports 50 instead of through a single opening, the lather will be divided into a plurality of relatively small streams and this will cause a final packing so that as it finally leaves the spout of the nozzle 49, it will have the desired thickness and smoothness to provide a very good shaving lather.

When this device is in use, the soap is placed upon the soap carrying platform and the cover or cap will be screwed tightly into place to close the upper end of the cup 1. The closure valve 3 can then be brought into engagement with a water spigot and when moved inwardly the water will flow into the cup through the spout 2 and fill the cup to the point shown in Fig. 2. The valve 3 may then be allowed to move to a closed position and the cup, if of minimum size will contain sufficient water to make lather enough for a single shave. It should be noted that since the opening 41 is at the center of the cap, water cannot flow through the screen 45 when the device is tilted in using or even placed upon its side upon a counter. The valve 20 will be moved to an open position in order to permit air from the receptacle 16 to pass up through the plug and neck or if the form shown in Fig. 7 or Fig. 8 are in use, the diaphragm 25 will be moved to cause air to pass upwardly through the neck 9, or the bulb 29 squeezed so that the air will pass up through said neck. As this air passes upwardly through the aforesaid neck, it enters the passage 36 of the soap platform and passes out through the side openings 35 which are positioned between the ribs 34 of this platform. This air passes between the ribs until it reaches the periphery of the platform and will then pass upwardly through the water in a spiral path and cause the water to be stirred to dissolve the soap. As the air passes up through the soapy water, soap bubbles are formed which move upwardly in the cup 1 and pass up through the screen 45 into the cup or sleeve 43. As previously explained, the passage of the soap bubbles through the screen 45 causes them to be broken up and reduced in size and these bubbles which will now be partially formed into a lather or soap suds will pass out through the opening 44 into the interior of the cap between the sleeve and depending side wall of the cap. The partially formed lather will then pass around the sleeve and in so doing will pass through the screens 52 which will cause further breaking up of the bubbles and reduce the lather to the desired consistency. This lather will then pass out through the passage 48 and upon reaching the upper end of this passage will be divided into small streams which will pass through the ports 50 and out of the discharge spout in a flat or ribbon-like mass. This lather may be fed directly upon the face of the person who is to be shaved or it may be caught in the hand and rubbed upon the face. This lather will thus be formed without it being necessary to make use of a shaving brush and will be delivered in a sanitary condition upon the face. Since the cup, if of minimum size which is preferable only holds approximately the amount of water necessary to make sufficient lather for one shaving, it must be filled for every shaving and therefore may be filled with warm water for each shave and further the soap

will not be left standing in a quantity of water when not in use. The container 16 will hold sufficient compressed air to last for sometime and therefore need not be replenished for every shaving. When the air in the container is below the necessary amount of pressure, it is simply necessary to place the valve-controlled inlet against the valve-controlled outlet of a filling pipe and 10 the air can be replenished. When it is desired to clean the device, the cap 37 will be removed and the disk 39 which forms the bottom of this cap will thus be released and can be removed. After the cap has been removed, the soap platform can be unscrewed and lifted from the bottom of the cup. Ordinarily, it is not necessary to clean the 15 depending neck 9 and plug 12 but if necessary the plug can be removed and the neck portion 20 9 and plug thoroughly cleaned. In the form shown in Figs. 1 and 2, it will be necessary to remove the bracing bars 19 before the plug 12 can be unscrewed from the neck 9 and in the form shown in Figs. 25 7 and 8, it will be necessary to remove the base before access may be had to this part.

The method or process of forming lather described herein is claimed in my co-pending application Serial No. 699,133 filed 30 March 13, 1924, which is division of this application.

For the foregoing, it will be seen that in addition to the novel manner of making the soap bubbles in the cup or receptacle 1, I 35 have provided between the latter and the lather outlet or discharge a novel means of condensing the suds into a thick lather, which consists preferably in the use of a plurality of spaced screens through which 40 the suds must pass. These screens may be of various forms and variously located. In all instances, however, each screen will be sufficiently fine to break the soap bubbles or suds into a myriad of minute soap cells and 45 to hold them against forcible outrush, while permitting said cells to slowly ooze outwardly. It is by so doing that the lather is made of the proper consistency and is prevented from being sprayed out of the outlet. The compartments, one or more as may 50 be found necessary or desirable, between the spaced screens, form condensing chambers for the suds and in practice I have found that the arrangement shown in Figs. 2, 4 55 and 6 of the drawings will produce a suitable lather for shaving purposes. I wish it understood however that this arrangement may be varied and if desired I may use the adjustable valve shown in Figs. 9 and 10 to 60 vary the thickness or consistency of the lather. As there shown the sleeve or compartment 43^a is formed with openings 44^a which open into each of the compartments formed by the screens 52^a and web 47^a; and 65 in the sleeve 43^a is a rotary valve 58 having

a hollow lower portion with a port or opening 59 which may be brought into register with any of the ports 44^a. A handle 60 on the upper end of this rotary plug or valve 58 permits it to be turned or adjusted according to the number of screens it is desired that the suds must pass through before being discharged from the device. By this means the thickness of the lather may be varied at will by simply turning the handle 60. 75

I claim:

1. A shaving lather forming device comprising a container for soap bubbles under fluid pressure, said container having an outlet for the bubbles with no liquid other than 80 their vesicles, and bubble-breaking means associated with said outlet for breaking up the soap bubbles into a myriad of minute soap cells and preventing forcible outrush of these cells through the outlet, while permitting them to ooze slowly from said outlet in the form of a thick creamy lather for 85 shaving purposes.

2. A shaving lather forming device comprising a container for soap bubbles under 90 fluid pressure, said container having an outlet, and a fine bubble-breaking screen for said outlet against which the bubbles with no liquid other than their vesicles are forced by the fluid pressure to break them into a 95 myriad of minute soap cells, said screen being sufficiently fine to prevent rapid outrush of said cells under the influence of the fluid pressure, while permitting them to ooze slowly through the screen and from the outlet in the form of a thick creamy lather for 100 shaving purposes.

3. A shaving lather forming device comprising a container for a saponaceous liquid, 105 said container being provided with an outlet above the liquid level for bubbles with no liquid other than their vesicles, said container having a fluid pressure inlet below the liquid level for generating soap bubbles from the liquid, and bubble-breaking means associated with said outlet for breaking up the soap bubbles into a myriad of minute soap cells and preventing forcible outrush of these cells through the outlet, while permitting them to ooze slowly from said outlet in 110 the form of a thick creamy lather for shaving purposes.

4. A shaving lather forming device comprising a container for a saponaceous liquid provided with an outlet above the liquid level, 120 said container having a fluid pressure inlet below the liquid level for generating soap bubbles from the liquid, and a fine bubble-breaking screen for said outlet against which the bubbles with no liquid other than 125 their vesicles are forced by the fluid pressure to break them into a myriad of minute soap cells, said screen being sufficiently fine to prevent rapid outrush of said cells under the influence of the fluid pressure, while per- 130

mitting them to ooze slowly through the screen and from the outlet in the form of a thick creamy lather for shaving purposes.

5. A shaving lather forming device comprising a container for a saponaceous liquid closed against gravitation of the liquid therefrom, a passage opening below the liquid level for admitting fluid under pressure to form soap bubbles above the liquid level, an outlet passage communicating with the bubble space only of said container, and a bubble-breaking screen for said outlet passage against which the bubbles with no liquid other than their vesicles are forced to break them into a myriad of soap cells, said screen being sufficiently fine to prevent rapid outrush of said cells under the influence of the fluid pressure, while permitting them to ooze slowly through the screen and from the outlet in the form of a thick creamy lather for shaving purposes.

6. A lather forming device comprising a receptacle to contain a saponaceous liquid, means for discharging air into the receptacle to co-mingle with the liquid and form soap bubbles above the latter, a condensing chamber communicating only with the portion of the receptacle above the liquid level, a screened opening affording communication between the receptacle and chamber, and a screened discharge for the condensing chamber, the two screens being sufficiently fine to prevent forcible outrush of the minute soap cells into which the bubbles are formed thereby, while permitting said cells to slowly ooze through the screen.

7. A lather forming device comprising a receptacle to contain a saponaceous liquid, means for discharging air into the receptacle to co-mingle with the liquid and form soap bubbles above the latter, a series of condensing chambers, one of which communicates with the receptacle and another of which has a discharge for the lather, and screens through which the suds must pass in passing from the receptacle to said lather discharge, all of said screens being sufficiently fine to prevent forcible outrush of the minute soap cells into which the bubbles are formed thereby, while permitting said cells to slowly ooze through the screen.

8. A lather forming device comprising a receptacle to contain a saponaceous liquid, means for discharging air into the receptacle to co-mingle with the liquid and form soap bubbles above the latter, a top for the receptacle having an outlet, a cap covering said top having a condensing chamber communicating with said outlet and a discharge for the lather, and spaced screens in said condensing chamber through which the suds or lather must pass in passing from the receptacle to said discharge.

9. A lathering device comprising a re-

ceptacle having a supporting surface for a cake of soap and adapted to contain a quantity of water, means for discharging air under pressure into the water around the soap-supporting surface to agitate the water and form soap bubbles, and means for converting the soap content of the bubbles to a smooth lather and for preventing spraying of the lather from the receptacle.

10. A lather forming device comprising a receptacle to contain a limited quantity of water, and having a holder for positioning a cake of soap in spaced relation to the receptacle wall, means for injecting air into the water to give it a whirling motion around the soap cake to create soap bubbles and evenly wear the cake, a lather discharge, and means interposed between the discharge and the receptacle for converting the soap bubbles to a thick lather and for preventing spraying of the lather from the receptacle.

11. A lather forming device comprising a receptacle for a saponaceous liquid having an air inlet below the liquid level for admitting air under pressure to co-mingle with the liquid and form soap bubbles, a lather chamber having a lather outlet and an inlet, the latter communicating with said receptacle above the liquid level to receive bubbles only with no liquid other than their vesicles, and means in said lather chamber for breaking up the soap bubbles into minute soap cells and preventing forcible discharge of said cells, while permitting them to ooze slowly through said chamber, forming a relatively thick lather for passage through the outlet of the lather chamber.

12. The structure of claim 11 having the lather chamber formed in a cap extending over the entire soap and water receptacle.

13. The structure of claim 3 having said outlet passage centrally disposed with respect to the upper end of said container, said container having a combined inlet and overflow preventing filling to an extent sufficient to reach said outlet passage when the receptacle is tilted.

14. The structure of claim 11 having the lather chamber provided with its inlet intermediate its diameter; said bubble breaking and converting means comprising a sleeve positioned about the inlet and dividing the lather chamber into an inner compartment and an outer compartment extending about the inner compartment, the outer compartment having an outlet and the sleeve having a passage providing communication between the compartments, and a partition in the outer compartment between the outlet and passage.

15. The structure of claim 11 having the lather chamber provided with its inlet intermediate its diameter; said bubble break-

ing and converting means comprising a sleeve positioned about the inlet and dividing the lather chamber into an inner compartment and an outer compartment extending about the inner compartment, the outer compartment having an outlet and the sleeve having a passage providing communication between the compartments, a partition in the outer compartment between the outlet and passage, bubble breaking means in the outer chamber, and bubble breaking means at the inlet.

16. A lather chamber having a top, bottom and side walls, the bottom being provided with an inlet opening, a sleeve about the inlet opening dividing the chamber into inner and outer compartments and having an opening providing communication between the compartments, an outlet for the outer compartment, and bubble breaking means for converting the lather into a thick and condensed mass while passing through the lather chamber.

17. A lather chamber having a top, bottom and side walls, the bottom being provided with an inlet opening, a sleeve about the inlet opening dividing the chamber into inner and outer compartments and having an opening providing communication between the compartments, an outlet for the outer compartment, a bubble breaking screen at the inlet opening, a partition in the outer compartment between the outlet and passage of the sleeve, and bubble breaking screens in the outer compartment.

18. A lather forming device comprising a receptacle for a saponaceous liquid having an air inlet below the liquid level for admitting air under pressure to co-mingle with the liquid and form soap bubbles, a lather chamber having a lather outlet and an inlet, the latter communicating with said receptacle above the liquid level to receive bubbles only with no liquid other than their vesicles, and means in said lather chamber for breaking up the soap bubbles into minute soap cells and preventing forcible discharge of said cells, while permitting them to ooze slowly through said chamber, forming a relatively thick lather for passage through the outlet of the lather chamber, the lather chamber being provided with its inlet intermediate its diameter; said bubble breaking and converting means comprising a sleeve positioned about the inlet and dividing the lather chamber into an inner compartment and an outer compartment extending about the inner compartment, the outer compartment having an outlet and the sleeve having a passage providing communication between the compartments, a partition in the outer compartment between the outlet and passage, a bubble breaking means in the outer chamber, and bubble breaking means at the inlet, the lather outlet which is in communication with the outer compartment being in the form of an outlet spout provided with a plurality of restricted lather passages.

19. A lather forming device comprising a water receptacle, a soap cake supporting platform spaced above the bottom of the receptacle, and an air inlet into the space beneath said platform, said space being in communication with the receptacle at the edge of said platform.

20. A lathering device comprising a soap and water cup having an air inlet in its bottom, a soap carrying platform spaced above said bottom, and passages between said platform and bottom leading to the edge of the former from said air inlet.

21. A structure as specified in claim 20, said passages advancing circumferentially of the platform from its center to its edge.

22. A lathering device comprising a soap and water holding cup having an air inlet in its bottom, a soap carrying platform in said cup having a depending neck provided with an air passage receiving air from the inlet of said cup, said neck having side ports extending radially within the cup for directing air towards the sides of the cup beneath the soap platform.

23. A lathering device comprising a soap and water holding cup provided with an air inlet in its bottom, a soap carrying platform in said cup having a depending neck provided with an air passage receiving air from the air inlet of said cup, said neck having side ports extending radially within the cup and ribs upon the under face of the platform positioned between the side ports and extending radially of the platform for directing air towards the sides of said platform and cup.

24. A lathering device comprising a soap and water holding cup provided with an air inlet in its bottom, a soap carrying platform in said cup having a depending neck provided with an air passage receiving air from the air inlet of said cup and having side ports extending radially within the cup and ribs upon the under face of the platform positioned between the side ports and extending radially of the platform for directing air towards the sides of the cup, said ribs being curved longitudinally to impart a whirling motion to the air when moving upwardly from beneath the platform.

25. In combination, bubble condensing means, a bubble-forming liquid-holding chamber having its bubble space in communication with said bubble condensing means, said chamber having an air inlet below the liquid level, and a check valve for said air inlet adapted to admit air below predetermined pressure to said chamber but movable beyond its open position to a second closed position under excess pressure through said inlet.

26. The structure of claim 3 having the container provided with a check valve in said fluid pressure inlet normally positioned at an outer closed position with respect to the container and movable inwardly to permit fluid under pressure to pass through the same, said valve means moving inwardly to a second closed position when acted upon by fluid pressure above a predetermined extent. 40
27. The structure of claim 3 together with a fluid pressure tank forming a base discharging into said fluid pressure inlet, a manually operated valve for controlling passage of fluid pressure from said tank through said fluid pressure inlet, and valve means in said fluid pressure inlet in a normally closed position and movable to an open position by fluid pressure passing from the tank through said pressure inlet when the manually operated valve is opened. 50
28. The structure of claim 3 having the container provided with a depending neck in which said pressure inlet is formed, valve means in said neck, a base for said container, and means for admitting fluid pressure to said base, the interior of said base being in communication with said pressure inlet. 55
29. A lather forming device comprising a receptacle to contain a saponaceous liquid, means for injecting air into the liquid to form soap bubbles above the same, a lather outlet, a plurality of suds-condensing compartments separated by screens, and a valve device for controlling the passage of the suds through a greater or less number of said compartments in its passage from the receptacle to the outlet. 70
30. A shaving lather forming device comprising a receptacle to be partially filled with saponaceous liquid, means for discharging air into the receptacle below the liquid level to form soap bubbles above the liquid level, a condensing chamber or passage communicating only with the portion of the receptacle above the liquid level and having a lather outlet, and a series of spaced bubble-breaking screens in said condensing chamber or passage against which the bubbles are forced with no liquid other than their vesicles, whereby to convert the bubbles into a myriad of minute soap cells and prevent forcible outrush of such cells to the outlet, while permitting them to slowly ooze through the screens and through said outlet. 75
31. A shaving lather forming device comprising a liquid receptacle having a soap cake supporting surface, means for admitting air under pressure into the liquid around the soap cake supporting surface, whereby to form bubbles above the liquid level, a condensing chamber communicating only with the portion of the receptacle above the liquid level and having a lather outlet, and a series of spaced bubble-breaking screens in said condensing chamber against which the bubbles are forced with no liquid other than their vesicles, whereby to convert the bubbles into a myriad of minute soap cells and prevent forcible outrush of such cells to the outlet, while permitting them to slowly ooze through the screens and through said outlet. 80

In testimony whereof I have hereunto set my hand.

ROBERT HUDSON WAGER.
